(57) **CLAIM**

The ornamental design for a portion of a display screen with animated graphical user interface, as shown and described.

DESCRIPTION

FIG. 1 is a front view of a first image of a first embodiment of a portion of a display screen with animated graphical user interface showing our new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of an eighth image thereof;

FIG. 9 is a front view of a ninth image thereof;

FIG. 10 is a front view of a tenth image thereof;

FIG. 11 is a front view of an eleventh image thereof;

FIG. 12 is a front view of a twelfth image thereof;

FIG. 13 is a front view of a thirteenth image thereof;

FIG. 14 is a front view of a first image of a second embodiment of a portion of a display screen with animated graphical user interface showing our new design;

FIG. 15 is a front view of a second image thereof;

FIG. 16 is a front view of a third image thereof;

FIG. 17 is a front view of a fourth image thereof;

FIG. 18 is a front view of a fifth image thereof;

FIG. 19 is a front view of a sixth image thereof;

FIG. 20 is a front view of a seventh image thereof; and,

FIG. 21 is a front view of an eighth image thereof.

In the first embodiment, the appearance of the transitional image sequentially transitions between the images shown in FIGS. 1 through 14. In the second embodiment, the appearance of the transitional image sequentially transitions between the images shown in FIGS. 15 through 21. The process or period in which one image transitions to another image forms no part of the claimed design. The broken line showing of a portion of a display screen in FIGS. 1 through 21 forms no part of the claimed design. The broken line showing of text and portions of the graphical user interface in FIGS. 1 through 21 represents environmental subject matter and forms no part of the claimed design.
